T. LARSSON

TUNNEL KILN

Filed Jan. 22, 1924

UNITED STATES PATENT OFFICE.

THURE LARSSON, OF WORCESTER, MASSACHUSETTS, ASSIGNOR TO NORTON COMPANY, OF WORCESTER, MASSACHUSETTS, A CORPORATION OF MASSACHUSETTS.

TUNNEL KILN.

Application filed January 22, 1924. Serial No. 687,679.

To all whom it may concern:

Be it known that I, THURE LARSSON, a citizen of the United States of America, residing at Worcester, in the county of Worcester and State of Massachusetts, have invented certain new and useful Improvements in Tunnel Kilns, of which the following is a full, clear, and exact specification.

My invention relates to tunnel kilns and more especially to an improvement in the construction of those of the muffle type in which the combustion of gases do not contact with the ware.

In the muffle type of tunnel kiln, various constructions have been employed for pre-heating the air which is used in the combustion zone and for cooling the ware after it has been fired at the maximum temperature. This has been effected by conducting air from the outside of the kiln through pipes disposed along the side wall of the kiln chamber in the cooling zone, where it accumulates heat from the ware which has been fired, and introducing it into the combustion chamber. The air surrounding the trucks of the kiln cars which are commonly used for conveying the ware through such kilns, accumulates some of the heat which escapes from the car body, and this air has also been used in the combustion of the fuel. Such arrangements depend upon the conduction of heat from the ware and kiln chamber through the walls of the air flue or conduit through which the air to be used for combustion is led to the combustion chambers. As a consequence, the cooling operation is not efficient, and considerable heat which might be used in the combustion zone is lost. Furthermore, such constructions do not provide a flexible method of firing and cooling the ware at a desired rate and according to an easily regulatable temperature curve.

It is accordingly an object of my invention to construct a tunnel kiln in which the ware which has been fired may be as rapidly cooled as its characteristics and mode of treatment will permit, and to convey as much of this heat as possible to the air which is to be supplied to the combustion chamber or to other portions of the kiln.

It is a further object of this invention to provide means for controlling the temperature conditions within the cooling and heating zones of the kiln, whereby the heating

and cooling curve of the kiln, and consequently of the ware being fired, may be more fully regulated than has heretofore been possible.

With these and other objects in view, as will be apparent from the following disclosure, my invention resides in the combination of parts set forth in the specification and covered by the claims appended hereto.

In the drawings illustrating one embodiment of my invention:

Figure 1 is a longitudinal vertical section, partly broken away, of the kiln, on the lines 1—1 of Figs. 2 and 3;

Figure 2 is a transverse section on the line 2—2 of Fig. 1; and

Figure 3 is a similar section on the line 3—3 of Fig. 1. On Figure 1 A B represent the preheating zone, C D the heating zone and D E the cooling zone.

In accordance with my invention, I provide a tunnel kiln, which has suitable means for heating the central zone thereof, with regulatable openings from the external atmosphere into the cooling zone of the kiln chamber, and preferably a plurality of such openings spaced apart, whereby air may be introduced into the cooling zone in desired volume to vary the temperature conditions as may be required for the particular ware being treated. I furthermore provide an air conduit adjacent the cooling zone of the kiln for withdrawing air from the kiln chamber. In order that the temperature curve within this portion of the kiln may be controlled, a number of suitably spaced openings from the kiln chamber into this air conduit are provided. These openings are so located that air may be withdrawn from any portion of the cooling zone and are regulated by valves controlled from the exterior of the kiln so that air may be withdrawn through any or all of them at such rate as may be desired. In kilns of this type, it is customary to heat the central portion by means of a combustion chamber or muffle extending longitudinally of the kiln, any suitable fuel such as oil or gas being used for this purpose. In the present invention, I may pass the air, which is drawn from the cooling zone of the kiln, into this chamber to support the combustion of the fuel or to vary the temperature conditions therein, and I may introduce regulatable amounts of this heated air into va-

100
105
110

rious portions of the combustion chamber, or by-pass any or all of it to an outlet.

In the specific embodiment of my invention illustrated by the accompanying drawings, I provide a tunnel kiln having foundation walls 1 upon which are built the outer vertical side walls 2 which are joined together by the roof 3 and held in place by the steel plates or girders 4 and cross rods 5. The foundation walls 1 are spaced apart leaving a floor space 7 along which are laid the tracks 8 upon which the kiln cars 9 are adapted to pass through the kiln. Along the inner edges of the foundation walls 1 are provided troughs 11 which form sand seals with the flanges 12 on the sides of the kiln cars.

In order to provide an enclosed muffle or kiln chamber 10 through which the kiln cars and ware may travel, inner vertical walls 13 are built along the inner edges of the foundation walls 1, spaced apart from the outer side walls 2 and joined to the roof wall 3 throughout the length of the kiln. From the cooling zone of the kiln chamber, a number of longitudinally spaced openings 14 are provided through the roof wall 3 to the exterior of the kiln for the passage of air, each having a slideable member 16 by which it may be regulated.

An air conduit 17 is formed on each side of the cooling zone of the kiln chamber by the lower portion of an inner vertical wall 13, the corresponding foundation and side walls 1 and 2 respectively, a kiln wall 18 at one end, a baffle wall 19 at the opposite end and a horizontal partition 21. In each of the vertical side walls 13 and below the horizontal partitions 21 the openings 23 are provided, which connect the kiln chamber and said air conduit 17. Above each of the air conduits 17 is provided a similar and larger air conduit 24 which is enclosed by the upper portions of an inner vertical wall 13 and of the corresponding outer side wall 2, the roof wall 3, an end kiln wall 18, a baffle wall 26 and partially enclosed at the bottom by a horizontal partition 21, leaving a space 30 between said baffle wall 19 and baffle wall 26. Each of said horizontal partitions 21 between the air conduits 17 and 24 is provided with longitudinally spaced openings 27 which may be regulated from the exterior of the kiln by slideable members 28 inserted through the openings 29 in the outer walls 2.

In the central and heating zone of the kiln CD, the longitudinal combustion chambers 31 are each formed by an inner vertical wall 13, an outer vertical side wall 2, the roof wall 3, a horizontal partition 32, a refractory baffle wall 26 and one of the end kiln walls 18. The wall 13 in the heating zone is made of a suitable refractory material capable of withstanding high tem-

peratures, and in order that it may be laterally supported to prevent deformation when heated, I may form it of two L-shaped members which are arranged with the horizontal flanges 33 in contact and supported on the transverse partition 32. These flanges are shown as built into and tied with the inner refractory brick wall 34 which lines the vertical side walls 2 of the kiln and is spaced therefrom by suitable insulating material. In order to provide for a uniform distribution of heat in the muffle, the flanges are formed with numerous perforations, as shown.

Parallel to each combustion chamber and beneath it is an air conduit 35 formed by the foundation wall 1, the lower portion of the inner vertical side wall 34, a vertical wall 36 adjacent the refractory car body, one of the end kiln walls 18, the baffle wall 19 and the horizontal partition 32, this conduit opening into the cooling conduit 24 through opening 30 between said baffle wall 19 and the baffle wall 26. In each of said horizontal partitions 32 are longitudinally spaced openings 37 connecting the air conduits 35 with the combustion chambers 31, which may be regulated from the exterior of the kiln by the slideable members 38 inserted into slots 39 through the outer side walls. Burners 41 are inserted into each of the combustion chambers through openings 42 in the side walls 2 and 34 for the introduction of fuel. Outlets 43 are provided in the kiln walls at the ends of the combustion chambers adjacent the ware entrance. These outlets lead through flues 44 to the fan 45. It is to be noted that the end openings 46 in the conduit 35 communicate directly with flues 44 and so serve for by-passing a desired portion of the heated air around the muffles so that all of the air used in the cooling zone need not be fed into the muffle.

The particular tunnel kiln, which I have thus described and illustrated in the accompanying drawings, is representative of one of the muffle type in which my invention has been embodied. The method of operating it is in general similar to that for other tunnel kilns, in that the ware to be fired is loaded upon cars, which are run into the kiln chamber until it is filled from end to end. The cars are then successively withdrawn from the exit end and cars loaded with unfired ware are introduced at the entrance end of the chamber, by any well known means adapted for the purpose. The central or hot zone of the kiln is maintained at approximately the temperature to which the ware is to be treated, by operating the burners in the combustion chambers accordingly. Upon passing through the kiln, the ware is heated slowly to the maximum temperature at which it is usually held for

some time, called the "soaking" period, and then cooled gradually to such temperature as will permit its removal from the kiln. It is customary to make the rate of travel

5 through the kiln constant, determining the heating, soaking and cooling periods by the lengths of the corresponding heating-up, central and cooling zones of the kiln chamber respectively.

10 I have therefore provided for controlling the temperatures in the cooling zone of the kiln chamber by drawing regulatable amounts of air at atmospheric temperature from the exterior of the kiln into the kiln
15 chamber and in direct contact with the ware at such points as may be desirable, thus cooling the ware at any desired rate, absorbing the heat from it directly by the air thus introduced as well as through the walls
20 of the conduits through which such air is withdrawn from the kiln chamber. The flow of air which has been thus heated may be controlled as by the regulatable openings between the kiln chamber and the air conduit and may be used in the combustion chambers for ignition of the fuel or withdrawn directly from the kiln. In order that the air which is to be passed into the combustion chamber may not lower the temperature of combustion or prove insufficient to support it, means are provided for controlling the volume of such air to be introduced and its rate of flow by spaced regulatable openings, such as have been described.
30 The heated air which is to be withdrawn from the kiln without passing through the combustion chamber may be drawn through air conduits located adjacent the heating-up zone or through the end
35 of the combustion chamber opposite the location of the burners, and drawn off with the products of combustion, serving in either case to transmit heat to the incoming ware.
40

45 The ware, which has been held at the temperature of the hot zone for the desired length of time, may be cooled as rapidly as is consistent with its resistance to such temperature or heat changes or as slowly as would naturally result from the radiation of heat through the kiln walls, or at any desired rate between these limits. Moreover, 50 the temperature curve prescribed by the heat treatment employed may be closely followed by thus controlling the rate of cooling of the ware at the various portions of the cooling zone through which it passes. The heat is effectively removed from the ware in the cooling zone by the air coming into direct contact with it and is thus directly transferred to the combustion chamber or to such other parts of the kiln as may be desired. 55

Further advantages which are to be obtained by the application of my invention are that such ware may be cooled either from the maximum kiln temperature to the

temperature of the atmosphere or through any intermediate range of temperatures, and at the same time be under the control of the operator throughout the cooling period. As a consequence of these advantages, a kiln having a shorter cooling zone than would otherwise be necessary may be employed and the length of time required for any particular article to be passed through the kiln appreciably shortened. 75

It will be apparent from my disclosure that various modifications may be made of my invention by changes in the design or operation of any particular construction, but it is to be understood that such modifications or applications are considered as embodied in the following claims.

Having thus described my invention, what I claim as new and desire to secure by Letters Patent is:

1. A tunnel kiln comprising a foundation and side and top walls forming a kiln chamber for the passage of ware, means for heating the central zone of the kiln, means providing regulatable air openings from the external atmosphere into the interior of the kiln chamber which are spaced longitudinally of the cooling zone for varying the temperature curve thereof, and means for drawing air through said openings into the kiln chamber. 90 95

2. A tunnel kiln comprising walls spaced to form a kiln chamber for the passage of ware, said kiln having an air conduit disposed adjacent the cooling zone, means providing a plurality of spaced regulatable openings from different portions of the cooling zone of the kiln into the conduit for varying the temperature curve of the cooling zone and means for drawing air through said conduit. 100 105

3. A tunnel kiln comprising a foundation and side and top walls spaced apart to form a kiln chamber for the passage of ware, an air conduit in the cooling zone of the kiln, 110 a combustion muffle disposed longitudinally of the heating zone of the kiln, means providing a series of spaced inlet passages from the cooling zone of the kiln chamber to the air conduit, means for independently regulating the inflow of air through said passages, and means for drawing air from the cooling zone into said air conduit and from the kiln, 115

4. A tunnel kiln comprising a foundation and side and top walls spaced apart to form a kiln chamber for the passage of ware, an air conduit adjacent the cooling zone of the kiln, a combustion muffle disposed longitudinally of the heating zone of the kiln, means providing a series of spaced regulatable inlets into said air conduit from widely separated portions of the cooling zone of the kiln chamber, means providing a regulatable opening from said air conduit into said com- 120
125
130

- bustion muffle, and means for drawing air from the cooling zone of the kiln chamber through said air conduit, into and through said combustion muffle and from the kiln.
- 5 5. A tunnel kiln comprising walls arranged to form a kiln chamber for the passage of ware, an air conduit disposed adjacent the cooling zone of the kiln and having an air inlet from said zone, a combustion muffle disposed longitudinally of the heating zone of the kiln, means providing a series of regulatable inlets from the air conduit into longitudinally spaced portions of the combustion chamber, and means for drawing air 10 through the conduit and the combustion chamber.
6. A tunnel kiln comprising walls forming a kiln chamber for the passage of ware, a combustion chamber in the central zone of 20 the kiln, an air conduit in the cooling zone of the kiln, said kiln chamber having spaced air inlets from the exterior atmosphere into the cooling zone and a series of regulatable spaced openings into said conduit from the 25 cooling zone, said conduit opening into the combustion chamber, and means for drawing air from the exterior of the kiln into the kiln chamber, thence into the air conduit and through the combustion chamber.
- 30 7. A tunnel kiln comprising a foundation and side and top walls to form a kiln chamber for the passage of ware, an air conduit in the cooling zone, a combustion muffle in the heating zone, a series of spaced regulatable inlets from the cooling zone of said kiln chamber into the air conduit, a communication between the air conduit and the combustion muffle, and means for drawing air from the kiln chamber, through the air 35 conduit and through the combustion muffle.
8. A tunnel kiln comprising walls forming a kiln chamber for the passage of ware, a combustion chamber in the central zone of the kiln, an air conduit in the cooling zone 45 of the kiln, said kiln chamber having spaced air entrances from the exterior atmosphere to different portions of the cooling zone and an opening into said air conduit, means providing longitudinally spaced regulatable 50 openings from said air conduit into said combustion chamber, and means for drawing air into the kiln chamber through said entrances, thence through the air conduit and through the combustion chamber.
9. A tunnel kiln comprising walls forming a kiln chamber having an air entrance to the cooling zone, an air conduit adjacent to and having an opening leading from the cooling zone of the kiln chamber, a combustion chamber in the heating zone of the kiln 60 having an opening from said air conduit, means for drawing air into the cooling zone of the kiln through said air entrance into said conduit and thence in predetermined amounts through said combustion chamber 65 to an exit, and means for by-passing a portion of such air around the combustion chamber to the air exit.
10. A tunnel kiln comprising a foundation and side and top walls spaced apart to 70 form a kiln chamber for the passage of ware, an air conduit adjacent the cooling zone of the kiln chamber, means providing a series of regulatable openings from the cooling zone of the kiln chamber to the air conduit for varying the temperature curve 75 within the kiln, a combustion chamber disposed longitudinally of the heating zone of the kiln chamber, an air conduit adjacent thereto having a series of spaced regulatable openings into the combustion chamber, means for supplying combustible fuel to the latter chamber, and means for drawing air from the cooling zone of the kiln through 80 said air conduits and into the combustion chamber and for by-passing any or all of such air around the combustion chamber.
11. A tunnel kiln comprising a foundation and outer side and top walls forming a kiln chamber for the passage of ware, means including inner refractory walls spaced from the outer side walls forming a combustion chamber on each side of the central zone of the kiln, further inner walls cooperating with the outer walls in the cooling zone 90 forming a longitudinal air conduit, means providing a series of regulatable openings from the exterior atmosphere into the cooling zone of the kiln chamber, said air conduit having an air entrance from the kiln 95 chamber and an exit to said combustion chamber, and means for drawing air from the exterior atmosphere into the kiln chamber and thence through the air conduit and through the combustion chamber.

Signed at Worcester, Massachusetts, this 14th day of Jan., 1924.

THURE LARSSON.
